LUMINAIRE

Vearl S. Wince, Newark, Ohio, assignor to Holophane
Company, Inc., New York, N.Y., a corporation of Delaware

Filed May 19, 1967, Ser. No. 7,190

Term of patent 14 years

Int. Cl. D26—02

U.S. Cl. D48—23

FIG. 1 is a bottom perspective view of a luminaire showing the new design;

FIG. 2 is a side view of the luminaire of FIG. 1;

FIGS. 3 and 4 respectively represent top and bottom views of the luminaire according to FIG. 1; and

FIG. 5 is an end view of either end of the luminaire according to FIG. 1.

The dominant features of my design reside in the full line portions.

I claim:

The ornamental design for a luminaire, as shown and described.
